UNITED STATES PATENT OFFICE.

FRANK A. MOFFITT, OF CHICAGO, ILLINOIS.

LIFE-SAVING SUIT.

1,123,912.

Specification of Letters Patent.

Patented Jan. 5, 1915.

Application filed April 6, 1914. Serial No. 829,896.

To all whom it may concern:

Be it known that I, FRANK A. MOFFITT, a citizen of the United States, residing at Chicago, in the county of Cook and State 5 of Illinois, have invented certain new and useful Improvements in Life-Saving Suits, of which the following is a specification.

This invention relates to suits designed for life-saving purposes, and its object is to 10 provide a suit which can be quickly slipped on, and which is water-proof. The suit is in two parts, with a novel water-tight joint therebetween. The entire body of the wearer is incased and thus protected against 15 wet and cold.

With the herein stated object in view, the invention consists in a novel combination and arrangement of parts to be hereinafter described and claimed, and in order that the 20 invention may be better understood, reference is had to the accompanying drawing, in which—

Figure 1 is a front elevation of the suit, partly broken away; Fig. 2 is a cross-section 25 showing the joint between the upper and lower portions of the suit, and Fig. 3 is a vertical section of a head covering.

Referring specifically to the drawing, the suit is composed of an upper part or jacket 30 5, and a lower part or pantaloons 6 having integral boots 7. The boots have heavy metal soles 8. The sleeves of the jacket have tight fitting wrist portions 9 over which gloves or mittens 10 are slipped. The jacket 35 also has a tight fitting bell-shaped collar 11 with sufficient fullness below the same so that the clothing and the movement of the wearer's body will not pull the collar away from the neck. Around the waist is secured 40 a life-preserver belt 12 which extends under the arms. Straps 13 run from the legs to a waist encircling belt 14 or connection on the pantaloons. These straps are looped at their lower ends to pass under the boots and they 45 extend upward to the belt 14 on the outside of the legs. To the belt 14 are also attached two straps 15 which cross at the chest portion of the jacket and pass over the shoulders and extend down to the rear portion of 50 the belt. At the crossing of the straps is a ring 16 for the attachment of a line for lowering or lifting the wearer.

In order to provide a water-tight joint 55 between the upper and lower portions of the suit, the following structure is provided: On the outside of the waist band of the pan-

taloons 6 is fastened an encircling ring 17 having an outstanding horizontal flange 18. On the inside of the waist band is an encircling ring 19. Rivets or other suitable fastenings passing through the rings 17 and 19 and the waist band therebetween secure said parts together. To the flange 18, on top thereof, is secured a ring 20 having an up-standing flange 21 which encircles the ring 17 in spaced relation. In the bottom of the annular space between the ring 17 and the flange 21 is placed a ring 22 of rubber or other suitable packing material. To the bottom portion of the jacket 5 are secured 60 stiffening members comprising inner and outer rings 23 and 24, respectively, between which said bottom portion of the jacket is held by rivets or other fastening means 25 passing through said parts. The reinforced 65 lower portion of the jacket is adapted to enter the annular space between the ring 17 and the flange 21, and it is forced down to seat against the packing ring 22 by means of a bolt 26 pivoted at 27 to the outer edge 80 of the flange 18 and passing through a slot 28 in the outer edge of a flange 29 projecting horizontally outward from the ring 24. A nut 30 is screwed on the bolt 26 above the flange 29, and upon screwing the nut down 85 against the flange, the reinforced bottom edge of the jacket is firmly clamped against the packing ring 22, and a water-tight joint is produced between the upper and lower 90 portions of the suit. This joint as shown is made of angle iron but if made in large quantities would be cast to desired shape. A head covering 31 is also provided which extends down over the shoulders, and has a front sight opening on the outside of which 95 is mounted a sliding window 32, which may be closed or opened. Along the sides of the window opening are racks 33 engageable by catches 33^a for holding the window in adjusted position.

Above the window is a vizor 34. The covering is supported on the head of the wearer by a ring 35 mounted inside the same near the top, and spaced from the front portion by a spacing device 35^a. The top of the 105 head covering also has a ventilator 36, over the outer end of which extends a guard 37. The head covering extends down to the shoulders and fits against the head at the back and sides, but extends out from the 110 face in front.

It is to be understood, of course, that the

suit and the head covering are to be made out of rubber or some other suitable material which is water-proof.

I claim:

- 5 1. A life-saving suit comprising a separate upper body incasing part and a lower leg incasing part, a reinforcing ring secured to the bottom edge of the body incasing part and having an outstanding flange which is 10 slotted, a seat at the top of the leg incasing part to receive the reinforced bottom edge of the body incasing part, a packing in the seat, bolts pivoted to the seat and adapted to be passed through the slots of the afore- 15 said flange, and means for tightening the bolts.
2. A life-saving suit comprising a separate upper body incasing part and a lower leg incasing part, a reinforcing ring secured

to the bottom edge of the body incasing 20 part, a ring secured to the top of the leg incasing part and having an outstanding flange, a ring mounted on said flange and having an upstanding flange encircling the first-mentioned ring in spaced relation, a 25 packing in the space between the first-men- tioned ring and the encircling flange, into which space the reinforced bottom edge of the body incasing part is adapted to extend to engage the packing, and means for clamp- 30 ing said reinforced bottom edge against the packing.

In testimony whereof I affix my signature in presence of two witnesses.

FRANK A. MOFFITT.
